United States Patent

Des. 235,336
Patented June 10, 1975

235,336

REVERSIBLE SHUTTER

Albert M. Lee, Peoria, Ill., assignor to
HC Products Co., Princeville, Ill.

Filed Nov. 1, 1973, Ser. No. 411,709

Term of patent 14 years

Int. Cl. D25—02

U.S. Cl. D13—1 M

FIG. 1 is an elevational view showing one face of a reversible shutter showing my new design;

FIG. 2 is an elevational view showing the reverse face thereof;

FIG. 3 is a partial, enlarged cross-sectional view taken substantially along line 3—3 of FIG. 2; and

FIG. 4 is a transverse cross-sectional view taken substantially along line 4—4 of FIG. 1.

I claim:

The ornamental design for a reversible shutter, as shown.
